UNITED STATES PATENT OFFICE.

CHARLES SCHWARTZEN, OF KENOSHA, WISCONSIN.

RAILROAD-CROSSING APPARATUS.

1,389,535.

Specification of Letters Patent. Patented Aug. 30, 1921.

Application filed May 28, 1920. Serial No. 384,966.

To all whom it may concern:

Be it known that I, CHARLES SCHWARTZEN, a citizen of the United States, residing at Kenosha, in the county of Kenosha and 5 State of Wisconsin, have invented new and useful Improvements in Railroad-Crossing Apparatus, of which the following is a specification.

This invention relates to a railroad crossing apparatus and has for its primary object the construction of a railroad gate that may be more efficiently operated from a remote point and when in operative position will positively prevent the passage of a vehicle. 10 15 An object of the invention is the substantial manner of constructing the street gate and the manner in which the same moves to its operative position so that a vehicle will be positively held against passing onto the 20 track.

A feature of the invention is the novel manner of connecting the street gate to the pedestrian gate so that the two will operate simultaneously upon the movement of one of 25 the gates.

With these and other objects in view the invention will be better understood from the following detailed description taken in connection with the accompanying drawing 30 wherein:

Figure 1 is a diagrammatic view illustrating the relative position of the apparatus with relation to the track.

Fig. 2 is a sectional view.

35 Fig. 3 is a sectional view showing the street gate in elevation.

Again referring to the drawing illustrating one construction of my invention the numeral 1 designates a trough of any suitable 40 formation or construction embedded in the earth to one side of the track B. This trough supports a shaft 2 to which is secured a street gate 3. This street gate in one of its constructions consists of a top 4 and bottom 5 so arranged that when the 45 gate is inoperative the top 4 will form the top of the trough and when in operative position the bottom 5 will form the top of the trough. From this construction it will be 50 seen that when the gate is in operative position any pressure brought to bear against the gate will be substantially taken care of owing to the substantial manner in which the gate is associated with the trough; thus 55 it will be seen that a vehicle will positively

be held against moving onto the track. To materially reinforce the gate I may in practice use the reinforcing strips 6 and the reinforcing portions 7. Arranged within the gate is a signaling device, such as an electric bulb 8, the circuit of which is automatically closed by the switch 9 when the gate moves to operative position. A cable 10 has one end connected to the gate and passes around the pulley 11 supported by the post 12 to any suitable point to be manually or mechanically operated. A coil spring 13 is connected to the gate in a manner to return same to normal position when the tension is removed from the cable 10. The pedestrian 60 65 gate 14 is pivoted to the post as indicated at 15 and has a ball and socket connection 16 with the link 17. This link also has a ball and socket connection 18 with the gate 3.

From the foregoing description taken in 70 75 connection with the accompanying drawing it should be apparent that I provide a substantial form of gate that may be quickly and efficiently operated from a remote point and when in operative position will positively prevent the passage of traffic.

It is, of course, to be understood that the invention may be constructed in various other manners and the parts associated in different relations and, therefore, I do not desire to be limited in any manner except as set forth in the claims hereunto appended.

Having thus described my invention what I claim is:

1. A railroad gate comprising a trough 90 embedded in the ground, a gate swingably supported within the trough and consisting of a top and bottom arranged at an incline to each other so that when the gate is in normal position the top will form the top 95 of the trough and when in operative position said bottom will form the top of the trough, a cable for moving the gate to its operative position, and a spring for returning the gate to its inoperative position. 100

2. A railroad gate comprising a trough embedded in the ground, a gate swingably mounted within the trough and consisting of a top and bottom arranged at an incline to each other so that when the gate is in normal position the top will form the top 105 of the trough and when in operative position said bottom will form the top of the trough.

In testimony whereof I affix my signature.

CHARLES SCHWARTZEN.
